UNITED STATES PATENT OFFICE.

ARTHUR JUNGHANS, OF SCHRAMBERG, GERMANY.

SAFETY DEVICE IN CONNECTION WITH MECHANICAL TIME-FUSES FOR ARTILLERY-PROJECTILES.

4,115,677.

Specification of Letters Patent.

Patented Nov. 3, 1914.

Application filed June 5, 1913. Serial No. 771,826.

To all whom it may concern:

Be it known that I, ARTHUR JUNGHANS, privy commercial councilor, a subject of the King of Wurttemberg, residing at Schramberg, Wurttemberg, Germany, have invented new and useful Improvements in Safety Devices in Connection with Mechanical Time-Fuses for Artillery-Projectiles, of which the following is a specification.

10 The improvements relate to mechanical time-fuses of that kind, wherein a firing pin is operated by the release of a firing pin retaining means, under the control of a time-train (clock mechanism or the like), and 15 aims to provide certain improvements therein.

The invention resides in the means for affecting the release of the firing pin retaining means, and in the means and devices for effecting safeguards on the operation of said releasing means.

The invention further comprises means whereby adjustments may be made from the exterior of a shell, for adapting the mechanism for operation either upon impact or upon the elapse of a predetermined time.

Other features of improvement will appear hereinafter.

In the accompanying drawings, the improvements are shown in connection with a mechanical time-fuse. The special construction of the fuse may be of any suitable kind; the improvements may be applied with some slight constructive modifications to all fuses, 35 wherein the release of a tensioned firing pin is effected by a time-train, which effects the release of the firing pin to be unlocked for the time being by means of a locking disk and a locking lever coöperating there- 40 with.

Referring to the various figures of the drawing, Figure 1 is an elevation with parts broken away of the fuse showing the locking disk and lever coöperating therewith and the safety member (slide *e*) in the position of rest *i. e.* radially inward; Fig. 2 is a plan view of the locking disk, the safety member being in the same position as shown in Fig. 1; Fig. 3 shows one half of the locking disk with the safety member in the releasing position; Fig. 4 is a side elevation of Fig. 3; Fig. 5 shows the parts in the catch-position (for impact ignition); Figs. 6 and 7 represent another embodiment of 50 the safety member (in the form of a lever)

in the positions corresponding to Figs. 2 and 3; Fig. 8 shows the fuse mechanism with the casing removed, and shows the two firing pins for shrapnel and grenade shot, and the locking mechanism; Fig. 9 is a plan view showing the intermediate locking mechanism; Fig. 9^a shows another position of the intermediate locking mechanism; Figs. 10 and 11 show the lower part of the fuse with the firing pin for impact ignition (grenade) in a plan view and cross section respectively; Figs. 12 and 13 show the adjusting means for the two kinds of ignition (time and impact ignition) in the central position, Fig. 12 being a plan view and Fig. 13 a cross section; Figs. 14 and 15 show the respective parts in similar views in the position for impact ignition; Figs. 16 and 17 show the parts in the position for time ignition.

A locking disk *d* is rotatably mounted in the upper part of the mechanism (Figs. 1 to 8) and is adapted to be rotated by a time-train or other suitable mechanism when this is set in operation by the flight of the projectile. The locking disk *d* is provided with a slot *d'* into which a lever *f*, when said slot and lever are opposite, may fall. The lever *f* engages a long arm *g'* of a lever *g*, the short arm *g''* of which engages an arm *h'* of a lever having arms *h''* and *h'''* engaging the firing pin *i* and the pin *k* controlling the slide *l* which governs the action of the firing pin *n*. Now in order that in the case of an unintentional rotation of the disk *d* neither of the firing pins can operate to ignite one of the percussion caps, the safety arrangement is such that, in the state of rest, the slot *d'* of the locking disk *d* is kept permanently closed. The safety arrangement, according to the construction shown in Figs. 1-5, comprises a part *e* adapted to move radially on the locking disk *d* and be held in the locking position by a spring. When the projectile is fired the said part *e* is moved outwardly by centrifugal force so that it uncovers the slot *d'* and allows the lever *f* to fall therein and release the lever *g*, which thereupon releases the lever *h'* and permits one or other of the firing pins *i* or *n* to act according to the setting of the control mechanism hereinafter described. The lever *f* is held in vertical position by contact with the full edge of the disk *d*, and it in turn holds the lever *h'* in vertical position.

through the intermediary of the lever *g*. When in vertical position the lever *h* holds the firing pin elevated against the pressure of its spring *j* and holds the pin *k* against rising and consequently holds the slide *l* against outward movement and consequent release of the firing pin *n*.

Now with regard to the details of the construction shown in Figs. 1-5, the rotatable or locking disk *d* is mounted on the spindle *d'* of the time-train over the upper frame plate I (Fig. 8). The said disk *d* is held on the spindle by friction and, since in the state of transport, no part protrudes laterally over its periphery, the disk can be rotated in both directions of rotation during adjustment. It carries on its upper side the slide *e* adapted to move outwardly against the action of a spring. The said slide *e* has a radially directed and downwardly bent lug or projection *e'* and a tangential lug or projection *e''* directed downwardly over the periphery of the disk; both lugs or projections are flush with the edge 25 of the disk in the transport (inactive) position of the slide (Fig. 2) so that there is no impediment to rotation in any direction. In this position, the lug *e''* covers the slot *d'* in the adjusting disk *d* which is adapted, during the time ignition, and after the expiration of the adjusted time, to permit the drop lever *f* which is pressed against the periphery of the adjusting disk *d*, to operate to bring about the ignition of the charge in 35 the shell. If the slide *e* is pushed outwardly (Fig. 3) in consequence of the centrifugal force produced by the rotation of the projectile, the lug *e''* uncovers the slot, so that the upper arm *f'* of the lever *f* can drop into the slot after a predetermined degree of rotation of the disk *d*.

If the adjusting disk is set for impact adjustment, the arm *f'* being located between the lugs *e'* *e''* the time train can then run 45 only until the arm *f'* bears against the lug *e'*, whereby the further movement of the time-train will be checked (Fig. 5).

According to the construction shown in Figs. 6 and 7, the safety member is not a 50 slide but a pivoted lever *e**, which, with its projection *e''** and *e'''** acts in the same manner as the slide *e* with its lugs *e'*, *e''*.

The lever *h* is adapted to be released in two ways; either—for time ignition—where 55 the end *f'* of the lever *f* drops into the slot *d'* of the adjusting disk and thus releases the levers *g* and *h* (whereby the locking of the pin *i* by the arm *h''* is annulled) or—for impact ignition—where the lever *g*, (which 60 is mounted with axial play) advances during the impact and thus directly releases the lever *h*, (whereby the locking of the pin *k* by the arm *h''* is annulled). In order that this axial advancement of the lever *g* cannot 65 take place during transport and also not too

closely in front of the gun, there is located between the lever *g* and the plate a locking lever *r*, which is so formed, that it is only oscillated into the free position by centrifugal force. It is held in the locking position by the 70 projection *s* which is rotated from the time-train in the direction of the arrow Fig. 9*, so that the lever *r* can oscillate outwardly and thus release the impact pin *k* only after covering a certain distance. The two pins *i*, 75 *k* are secured against longitudinal movement in the transport state by centrifugal dogs *i'* *k'* (Fig. 12). The arrangement is also such that when a locking member adapted to prevent a change of the adjustment for 80 the time of flight, etc., is thrown into the locking position, the adjustment of the kind of ignition will also be effected.

A holding or supporting lever *q* adapted to be adjusted laterally by being rotated out of a central position serves as an internal setting member. The said lever *q*, according to its adjustment to the right or left, is adapted to secure either the firing pin *i* for time ignition, or the locking pin *k* for 90 impact ignition. When securing one pin, the other pin is of course released and vice versa, so that for example, Figs. 14 and 15 of the drawings (where the lever *q* is turned to the right) show the setting the mechanism for impact ignition in consequence of the securing of the firing pin *i* and the release of the locking pin *k*. In the outer flange *t* of the fuse-body, there is mounted a pin *z*, which has a square head *z'* on its 100 outer end and carries on its inner end an eccentric pin *z''*, which engages in a slot of the holding or supporting lever *q*. In approximately the middle of its length, the pin *z* has a further eccentric portion *z'''* in 105 which bears a locking pin *z''** adapted to slide in a bore in the flange parallel to the axis of the projectile. The upper end of this pin *z''** lies underneath the flat spring *z⁵*, (which is inserted in a suitable recess or depression) and has a point *z''''*, which, when pressed upwardly by the portion *z'''* of the pin *z*, is adapted to penetrate into the edge portion *Z* of the cap which serves for the 110 adjustment at the time-mechanism (i. e. disk *d*), whereby the arbitrary rotation of the 115 said cap is prevented.

On the outside of the rotary pin *z*, there is preferably provided an index *X*, which, when the locking member *z''** is disengaged 120 and the supporting lever *q* is in the central position, clearly indicates the position of rest and central position respectively of the parts by its upright position (Fig. 1). The rotation of the pin *z* to effect the locking of 125 the cap and also the adjustment of the ignition are effected in a simple and quick manner by means of a key fitting upon the square head, *z'* of the pin, the setting for 130 time-ignition (Figs. 16 and 17) or impact

ignition (Figs. 14, 15) depending on the turning of the key either to the left or right. In both cases, however, no matter whether the pin z is turned to the right or left, the pin z^4 will be lifted by the eccentric z^3 and the point z^6 of the flat spring z^5 will thus be pressed into the cap, whereby the arbitrary rotation of the latter will be prevented. By means of the spring z^5 , the pins z^4 will be held pressed against the eccentric portion z^3 , whereby the pin z , the frictional engagement of which is such that it can hardly be turned without a key, is completely secured against any displacement during the flight of the projectile.

It is obvious that both in connection with the adjustment for the time ignition and for the impact ignition *i. e.* in both cases, the locking member is moved to locking position for preventing changes of the position of the locked parts, while, when the parts are in the central position (Figs. 12 and 13) the locking member is in the release position.

25 A simple beveling may be provided instead of the eccentric portion z^3 , whereby the full part of the pin z would produce the eccentric effect. In the latter case, however, it would be necessary to prevent, by means of a screw or the like, the pin from flying out in consequence of the centrifugal force.

I claim:—

1. In mechanical time-fuses, the combination of a firing pin, a lock therefor, a rotatable disk for controlling the action of said lock, and centrifugally operated means on said disk for controlling the action of said lock.

2. In mechanical time-fuses, the combination of a firing pin, a lock therefor, and means for controlling the action of said lock, said means comprising a rotatable disk having a slot therein, means coöperating with said slot for operating said lock, and centrifugally operated means on said disk controlling the coöperation of said means and slot.

3. In mechanical time-fuses, the combination of a firing pin, a lock therefor, and means for controlling the action of said lock, said means comprising a rotatable disk having a slot therein, means coöperating with

said slot for operating said lock, and a spring-controlled rotatable safety lever 55 which normally closes said slot in said disk, and is adapted to uncover said slot under the action of centrifugal force due to rotation of the projectile.

4. In mechanical time-fuses, the combination of two firing pins, one for time firing and the other for impact firing, a lock for said firing pins, means controlling the action of said lock, and means adapted to lock one or the other of said firing pins against release by said first-named lock.

5. In mechanical time-fuses, the combination of two firing pins, one for time firing and the other for impact firing, a lock for said firing pins, means controlling the action 70 of said lock, and a lever adapted to be turned to lock one or the other of said firing pins against release by said first-named lock.

6. In mechanical time-fuses, the combination of two firing pins, one for time firing 75 and the other for impact firing, a lock for said firing pins, time-means for controlling the action of said lock, means for adjusting the action of said time-means on said lock, means adapted to lock one or the other of 80 said firing pins against release by said first-named lock, and means operated by said second-named locking means for locking said adjusting means against operation.

7. In mechanical time-fuses, the combination of two firing pins, one for time firing 85 and the other for impact firing, a lock for said firing pins, time-means for controlling the action of said lock, means for adjusting the action of said time-means on said lock, 90 a lever adapted to be turned to lock one or the other of said firing pins against release by said first-named lock, an eccentric pin adapted to operate said lever, and a pin operated by said eccentric pin, adapted to lock 95 said adjusting means against operation upon turning of said eccentric pin to operate said lever to lock one or the other of said firing pins.

In witness whereof, I have hereunto 100 signed my name in the presence of two subscribing witnesses.

ARTHUR JUNGHANS.
